US0D1094111S

(12) **United States Design Patent** (10) **Patent No.:** **US D1,094,111 S**
(45) **Date of Patent:** **** Sep. 23, 2025**

(54) **PACKAGE FOR CONTAINERS**

(71) Applicant: **Graphic Packaging International, LLC**, Atlanta, GA (US)

(72) Inventors: **Raymond R. Spivey, Sr.**, Mableton, GA (US); **Jon Thompson**, Bristol (GB); **Neil Jordan**, Bristol (GB)

(73) Assignee: **Graphic Packaging International, LLC**, Atlanta, GA (US)

(**) Term: **15 Years**

(21) Appl. No.: **29/898,807**

(22) Filed: **Aug. 1, 2023**

(51) LOC (15) Cl. **09-05**

(57) **CLAIM**

The ornamental design for a package for containers, as shown and described.

DESCRIPTION

FIG. 1 is a perspective view of the first embodiment of the package for containers showing our new design;

FIG. 2 is a left elevation view; the right elevation view being a mirror image thereof;

FIG. 3 is a front elevation view; the rear elevation view being a mirror image thereof;

FIG. 4 is a top plan view thereof;

FIG. 5 is a bottom plan view thereof;

FIG. 6 is a plan view thereof; shown in an unfolded configuration;

FIG. 7 is a perspective view of the second package for containers;

FIG. 8 is a left elevation view, the right elevation view being a mirror image thereof;

FIG. 9 is a front elevation view, the rear elevation view being a mirror image thereof;

FIG. 10 is a top plan view thereof;

FIG. 11 is a bottom plan view thereof; and,

FIG. 12 is a plan view thereof; shown in unfolded configuration.

(Continued)

The portions of the package for containers shown in broken lines form no part of the claimed design.

1 Claim, 12 Drawing Sheets
